1 Claim. (Cl. 24—79)

UNITED STATES PATENT OFFICE

BELT BUCKLE

Milton Medlin, New York, N. Y.

Application May 18, 1950, Serial No. 162,653

1

This invention relates generally to belt buckles and more particularly to a belt buckle designed to support a nether garment from the waist of the wearer.

It is one of the general objects of my invention to provide a buckle having new and improved means whereby the front portion of the trouser is held elevated against sagging with reference to the overlying belt.

A further general object of the invention is the provision of a new and improved belt engaging tongue for a trouser supporting belt buckle.

Another general object of my invention is the provision of a simple highly efficient and inexpensive belt buckle.

For the attainment of these objects and such other objects as may hereinafter appear or be pointed out I have illustrated one embodiment of my invention in the drawings wherein:

Figure 1 is a top plan view of the improved buckle.

Figure 2 is a perspective view thereof.

Figure 3 is a horizontal section taken centrally longitudinally through the front portion of a belt and the underlying trouser portions.

Upon reference to Fig. 2 it will be observed that the belt buckle shown there comprises a U-shaped frame 10 having a transverse pin or cross bar 11 which connects the free ends of the frame legs to complete a closed loop through which one end B1 of the belt strap is received for adjustment of its effective length. This type of buckle is generally provided with a tongue 13 engaged at one of its ends about the cross bar 11 for free swinging or swivelling thereabout to engage the distal and free end of the tongue through any one of the spaced apart openings generally provided centrally longitudinally of the belt. The other end B2 of the belt (shown in dotted lines in Fig. 2) has its central portion cut away inwardly from its extreme free edges as shown at B3 to provide two loops B4 and B5 which are engaged about the outer portions of the cross bar 11 to secure that end of the belt thereto. The cut away central portion of the belt end leaves an open space within which the pivoted end of the tongue 13 is secured and held centered between the loops B4 and B5 on the belt.

The feature of invention revolves about the construction of the tongue which I will now proceed to describe in detail. Upon reference to the drawings it will be observed that tongue 13 is shown as an integral part of a unit formed

from a bar or rod-like member of extended length. This member is bent back upon itself along its length at spaced apart points to provide three substantially parallel sections which are in overlapping relation. One of the outer of these sections forms tongue 13. The other of the outer sections forms a garment engaging hook 16. These two outer sections 13 and 16 are connected by intermediate section 18.

10 The following observations will be made as to these sections. The intermediate section 18 is formed from the rod-like member by a bend which takes the form of a loop 20. This loop 20 engages centrally about the cross bar 11 between loops B4 and B5 which secure the belt to the buckle and supports the unit for swivelling; the tongue 13 which extends integrally from one end of the loop 20, is of a length substantially greater than that of the intermediate member 18 and extends a substantial distance therebeyond to the left in the showing of Figs. 2 and 3; and the intermediate section 18 and the tongue 13 are shown in close adjacency. The outermost section 16 which forms the garment engaging hook is formed by giving the rod-like member a second bend 21 at a point along its length spaced from the point wherein the loop 20 is formed. The loop 20 and bend 21 thus define the length of the intermediate section 18. It will be observed further that the garment engaging hook or section 16 is of greater length than the intermediate section 18 and extends a substantial distance to the right beyond loop 20 and, in the preferred arrangement shown in Figs. 2 and 3, is spaced from the loop 20.

30 Fig. 3 of the drawings is a horizontal section through the top portion of the fly of the trousers and the portion of the belt (including the buckle) which normally overlies this portion of the trousers. In this figure the garment portions T1 and T2 overlap vertically centrally of the trouser front and define what is known as a fly. The integrated buckle tongue 13 and garment engaging hook 16 are so dimensioned and related that when a belt is engaged through the trouser belt receiving loops and closed at the front by the belt buckle, the garment engaging hook portion 16 will be enterable between the two overlying fabric sections T1 and T2 of the fly.

40 The fly of a pair of trousers is generally closed at or adjacent the top by interengaging elements on the two overlying fly portions T1 and T2. These cooperating elements may comprise button T3 secured to the inner of the two overlying fly portions by thread T4 and a buttonhole (not

shown), in the outer fly section, through which said button is engaged. Where the button is located so that its fastening threads T4 are approximately in the plane of the sections 13, 16 and 18, garment engaging hook 16 can serve its purpose in the manner shown in Fig. 1. In this relationship of the parts the button will rest on the hook 16 and will be held elevated thereby against sagging. For this arrangement the hook 16 can be spaced away from the loop 20 for a sufficient distance so that it will not have a gripping engagement with the inner fly portion interposed therebetween.

Where preferred the space between the hook 16 and the loop 20 may be decreased sufficiently so that the interposed inner fly portion T2 will be gripped therebetween. This arrangement may be found more desirable for example where the level of the button is such that its threads normally will not rest on hook 16.

The attachment of the belt buckle to the belt strap by means of the loop 20 and the engagement of the finger 13 through one of the openings in the belt strap to close the belt about the waist may be more or less conventional. However, the swivelling movement of the tongue 13 to engage its end through the belt strap will present the finger parallel with the trouser front and approximately in the plane between the two overlapping sections of the trouser fly. With the parts in this position an angular shift of the belt around the body will cause the tongue 16 to enter between the two fly portions to reach the position shown in Fig. 3.

It is to be understood that this invention is not to be restricted to the precise details of construction shown since various modifications and alterations may be made therein without departing from the scope of the invention or

sacrificing the advantages derived from its use.

Having thus described and illustrated my invention, what I claim as new and desire to secure by Letters Patent, is:

- 5 A tongue member having a loop for attaching it to a buckle frame of a waist engaging garment supporting belt to swivel the member on the buckle frame to engage and disengage the member from the belt; said tongue member being formed from a rod-like length of material by a bending operation into three portions aligned in overlapping relation, one of the outer of the aligned portions forming the tongue of the buckle and the other outer portion forming a garment attaching finger, the third and intermediate portion connecting the two outer portions to each other, the belt engaging tongue being connected to the intermediate portion of the member by a loop adapted to engage about a member of the
- 10 frame and swingingly support the member from the frame whereby when the member is swivelledly mounted on the frame by means of the loop, the engagement of the free end of the tongue with an opening in a belt strap will automatically position the finger in the plane between the overlapping portions of the fly of the nether garment so that the finger can be interposed between these fly portions for supporting the garment against sagging with reference to the belt.
